(57) **ABSTRACT**

This invention introduces a groundbreaking beanie design featuring a new stitch configuration, departing from conventional norms. Employing innovative stitch lining techniques, the crown of the beanie is artistically redefined, blending comfort with sophistication. The distinctive design involves two parallel vertical stitches interconnected by a solitary horizontal stitch, evoking the form of the letter "H" or the Greek letter Theta. The stitch lines exhibit fluidity, adapting seamlessly to fabric stretch when worn. This versatile stitch pattern is adaptable to both cuffless and cuffed beanies, signifying a versatile solution for diverse preferences. The invention revolutionizes beanie creation while accentuating the convergence of textile artistry and wearable functionality.

**CROSS-REFERENCE TO RELATED
APPLICATIONS**

Ser. No. 18/342,548 and Ser. No. 29/878,778 Filed on Jun. 27, 2023.

BACKGROUND OF THE INVENTION

The invention pertains to the fields of invention of clothing, garments, headwear, and apparel. The invention seeks to create a streamline and comfortable fit that differs from the current beanie stitch that is being used. The beanie H stitch's aim is to create a contoured fit to the crown of the head which allows a new take on comfort using the spacing and placement of the stitch at the peak or crown of the beanie.

**Description of Related Art: Including Information
Disclosed Under 37 CFR 1.97 and 1.98**

The related art depicts figures of the beanie and stitch design showcasing vertical parallel stitches connected by one horizontal stitch, creating the appearance of the English letter "H." The vertical stitches are located only at the peak of the crown and do not extend beyond that. The related art showcases different angles of the beanie, illustrating the stitch from multiple viewpoints.

BRIEF SUMMARY OF THE INVENTION

A beanie whose stitch alters from a traditional beanie. Its stitching components consist of two vertical parallel stitches connected by one horizontal stitch.

**BRIEF DESCRIPTION OF THE SEVERAL
VIEWS OF THE DRAWING(S)**

FIG. 1 shows:

5 hand rendered drawings of a beanie from alternating viewpoints titled: top stitch view, front stitch view, back stitch view, left stitch view, and right stitch view.

2

FIG. 2 shows:

A black and white photograph of the front of the beanie showcasing the horizontal stitch running along the top.

FIG. 3 shows:

5 A black and white photograph of the top of the beanie showcasing the full stitch pattern in the shape of two vertical lines connected by one horizontal line in which the spacing between vertical line 1 and vertical line 2 varies.

FIG. 4 shows:

10 A black and white photograph of the side of the beanie showcasing the side view of the stitch on the beanie.

FIG. 5 shows:

A black and white photograph of the inside of the beanie showcasing the stitch linings in the "H" design.

**DETAILED DESCRIPTION OF THE
INVENTION**

20 The invention showcases a new beanie design stitch. It uses stitch lining techniques to outline the crown of the head in a way that is comfortable and sleek. This new design uses two vertical parallel stitches connected by one horizontal stitch. This forms the appearance of the letter "H", or it may form the appearance of the Greek letter Theta. The lines may curve according to the stretch of the fabric/beanie when worn. This stitch may or may not be used on beanies with or without a cuff.

The invention claimed is:

30 1. The method for creating a beanie using the stitch, comprising of the steps:

Forming two vertical parallel stitches and connecting the two vertical parallel stitches with one horizontal stitch, creating an appearance resembling the letter "H", this includes varying the spacing between the two vertical parallel stitches to accommodate the stretch of the fabric/beanie when worn, this may be on beanies with or without a cuff. The parallel stitches do not extend to the brim of the beanie but rather sit at the crown of the head, at the peak and are bridged with a singular stitch.
